UNITED STATES PATENT OFFICE.

JACOB SILBERMAN, OF NEW YORK, N. Y.; CLARA SILBERMAN EXECUTRIX OF SAID
JACOB SILBERMAN, DECEASED.

PINTLE FOR HINGES.

Application filed December 9, 1925. Serial No. 74,333.

My present invention relates to an improvement in hinges for loose leaf ledgers and is an improvement over the pintle piece shown in my copending U. S. patent 5 application Serial No. 726,983, filed July 19, 1924, for improvement in hinges for loose leaf ledgers, and also relates to the method of making the cap piece.

My improvement consists in reinforcing 10 certain portions of the cap piece in such a manner as to strengthen it against breakage, and at the same time to prevent the working loose of the pintle.

In the drawings, Fig. 1 is a fragmentary 15 side elevation of my device shown assembled;

Fig. 2 is a perspective view of my improved plug or cap piece;

Fig. 3 is a fragmentary perspective view 20 of a portion of the tubular backing;

Fig. 4 is a side elevation of a portion of the hinge element which coacts with the pintle;

Fig. 5 is a sectional view taken on the 25 line 4—4 Fig. 4; and

Fig. 6 is a side elevation of my plug or cap piece partly in section.

In structures of this class and due to the 30 method of assembling the plug or cap pieces into the tubular backing element or binding bar 1, Figs. 1 and 3, it has been found in practice that in some instances the plug or cap piece generally denoted by 2, Figs. 2 and 6, on account of its peculiar construction requires some reinforcement at its narrower 35 section, this especially in view of the fact that it is preferred to make the cap piece of cast aluminum which is sometimes a little brittle and therefore subject to bending due 40 to the fact that these binders are utilized sometimes with a large number of inserted leaves and are therefore quite heavy.

In the construction shown, the plug or cap 45 comprises generally a base portion 3 upon which is mounted a tube filling portion or plug 4, which in contour is substantially in close fit with the interior walls of the tubular binding bar 1 as at 5. Fig. 3, so that when the bar is set over the plug 4 and 50 down on the top of the base portion 3, as shown in assembly at Fig. 1, the snug fit thereof, after being pinned by means of pins P, causes firm engagement with the tubular bar and holds the caps in axial alinement

one with the other at the top and bottom 55 as shown, the pintles engaging in a hinge fold formed on a butt member B.

A further element on the cap piece 2 is the pintle post or boss generally denoted by 6, which is cast integral with the portions 60 3 and 4, and standing upright from the base portion 3 a considerable amount so as to fully reinforce the spindle or pintle 7 later described.

The pintle or spindle 7 is made from a 65 piece of strong wire having at one end a long straight portion or leg 8 constituting a hinge pin projecting axially from the boss or post 6, the wire at its other end passing through the post and into the base 3 and 70 being there bent in U-shape, as at 9, and thence passing as a shorter straight portion or leg 8' through the filler plug 4 and extending somewhat above the upper side of the plug, this extending portion of the 75 shorter leg 8' resulting from the molding, later described, of the cap piece around the wire and having provided during the molding the means for engagement therewith of a suitable die, not shown, which also engages the longer leg 8 for holding the legs 8 and 8' in desired relation to each other 80 during the molding.

In the partial sectional view shown in 85 Fig. 6, it will be noted that the bent joining portion 9 of the pintle or spindle is integral with the legs 8, 8', and that in passing from the pivot portion 7 of the spindle to the offset position 8' of the shorter leg, the wire passes through the weakest portion of 90 the cast aluminum base 3, thereby greatly reinforcing the same against bending, due to the fact that the preferred form of construction contemplates the making of the cap piece of cast aluminum which is apt at 95 times to bend at the point α due to the thinness of the base portion 3 at this point.

In the manufacture of the cap piece, suitable dies, not shown, are so arranged as to engage and hold the upper portions or legs 100 8, 8' of the spindle wire in desired relation to each other, and molten aluminum is poured about the lower portions thereof including the bent portion 9, and upon the hardening of the aluminum, the bent portion and parts of the legs of the spindle are firmly embedded within the body of the aluminum cap piece and become substan- 105

tially integral therewith, at the same time reinforcing the cap piece at the desired parts thereof.

- The construction above noted also develops another desirable feature which is that the spindle wire 7 being arranged as described within the base 3 is prevented, when the binder is in use and of considerable weight, due to the loose leaf matter therein, from being forced through the bottom of the base 3 thereby weakening the entire structure and tending to scratch or mar the furniture upon which the binder is disposed.
- Referring to Fig. 2, the cap piece has a body portion composed of the base 3, the filler plug 4 thereon, the base 3 extending beyond the sides and ends of the plug, the post 6 located on the extended base 3 and spaced away thereon from the adjacent end of the plug 4, and the pintle 7 having a portion extending from the post 6 and constituting a hinge pin and a portion passing through the post 6 and bent to pass through the base 3 longitudinally thereof and through the plug 4 transversely thereof, the post 6 being spaced away from the adjacent end of the plug to permit one side of the

straight cross cut end of the binding bar 1 to pass between the post and the adjacent 30 end of the plug so that the edge of the straight cross-cut end of said bar bears at all parts of the edge upon the extended base 3 as shown in Fig. 1.

What I claim and desire to protect by 35 Letters Patent is:

A cap piece for loose leaf binders comprising a base member, a plug on one face of the base member spaced marginally therefrom throughout its extent to fit snugly 40 within the end of a binding bar with the end edge of the bar bearing against said face, a post projecting from said face of the base member in spaced relation to one end of the plug, and a pintle wire having a 45 leg embedded axially in the post with one end projecting therefrom, a second leg embedded in and extending into the plug, and a portion connecting the legs and embedded in the base member between the opposite 50 faces of the same and reinforcing the base member between the post and the plug.

Signed at New York in the county of New York and State of New York this 30th day of November, A. D. 1925.

JACOB SILBERMAN.
